12 Claims. (Cl. 14—36)

1

This invention comprises improvements in or relating to movable bridges, dock gates and the like. It is an object of the invention to provide means for moving a bridge, such for example as a bascule or like structure, which is heavy and which has to be periodically operated, which means are simpler and require a smaller power driving unit than is the case with constructions at present in use.

In operating a bascule bridge through the usual mechanism of a driving motor and reduction gearing a high starting effort is required from the motor on account of the weight of the parts which have to be set in motion and the power of the motor must be much greater than is necessary to complete the movement once the motion has been initiated. The same applies to other heavy parts such as swing bridges, lock gates and the like. Moreover, efficient braking means have to be provided to bring the parts to rest without shock at the end of the movement and with exactitude.

By the present invention the interposition of gearing for applying power to the moving parts and of separate braking means for stopping them may be entirely obviated.

According to the present invention in movable bridges, dock gates and the like there are provided operating means comprising a float operatively connected to the moving parts, a float chamber in which the float moves and means to fill and empty the chamber so as to set the moving parts in motion by the increase in effective weight of the float when the chamber is being emptied and by the decrease in effective weight when the chamber is being filled.

The invention further includes a bascule bridge comprising in combination a tiltably-mounted bridge girder, a counterweight therefor and means to vary the effective weight of the counterweight by adding or withdrawing liquid in contact therewith. In certain cases the weight of the counterweight may be varied by adding and withdrawing liquid to and from chambers in the counterweight itself, but generally the counterweight is located in a float chamber and the means for introduction and withdrawal of liquid are constituted by means for varying the liquid level in the float-chamber.

Preferably the float fits the float chamber in which it works closely so as to limit the quantity of liquid which requires to be transferred for operation and so as to damp the movements of the parts and to cushion the end of the move-

2

ment thereby obviating the need of any separate braking device.

The invention will now be described with reference to the accompanying drawings which show specific examples of bascule bridges constructed in accordance with the invention. In the drawings:

Figure 1 is a longitudinal section through a bridge and operating parts therefor according to one construction, the section of Figure 1 being taken upon the lines 1—1 of Figures 2 and 3 with certain parts broken away to show other parts behind them;

Figure 2 is a cross section approximately upon the line 2—2 of Figure 1 but with certain parts broken away and with the right-hand part of the figure shown in elevation;

Figure 3 is a plan, showing however the float chamber and adjacent parts in horizontal section;

Figure 4 is a vertical section through a regulating valve looking in the direction of the arrows 4—4 of Figure 5;

Figure 5 is a plan of the valve shown in Figure 4 with parts broken away to show the internal construction;

Figures 6, 7 and 8 are diagrams of pipe connections;

Figure 9 is a diagrammatic side elevation, and

Figure 10 is a cross section of an alternative construction of bridge.

Referring first to Figures 1 to 8, the bridge comprises a girder 11 which may span, say, a canal 12 and which in itself may be of the usual construction for a bascule bridge. The girder 11 has an abutment 13 at one end and is mounted on a pivot shaft 14 at the other end, the pivot shaft being arranged to come within an upper corner of a chambered structure 15 constructed of concrete and located at the opposite side of the canal 12 from the abutment 13. The structure 15 has, over the greater part of its width, a roof section 16 which is of the same height as the floor of the girder 11 and constitutes a roadway on to the bridge when the girder 11 is horizontal. On the pivot shaft 14 there are mounted three counterweights 17, 18, 19. The counterweights 17, 18 are located in chambers 20 beneath the roadway 16 and balance the greater part of the weight of the girder 11. The counterweight 19 is located in a float chamber 21 to one side of the roadway and the counterweight 19 is of such weight that if the float chamber 21 is empty it will be able to raise the girder 11 into the position shown in chain lines in Figure

1, whereas if the float chamber 21 is filled with liquid up to the level of the mark shown at 22, in Figures 1 and 2, the girder 11 will just touch the abutment 13. If the float chamber 21 is filled a little further to the level of the mark 23 the girder 11 will be held firmly down on the abutment 13. The counterweights 17, 18, and 19 are of sector-like shape as seen, for the counterweight 19, in Figure 1, and the general shape of the float chamber 21 in which the counterweight 19 works is that of a quadrant having a curved wall 24 nearly concentric with the shaft 14, a vertical wall 25 shutting off the float chamber from the canal 12 and a top 26 which forms the underside of a reservoir 27 for liquid. Adjacent to the reservoir 27 there is a pump house 28, the reservoir 27 and pump house 28 being located to one side of the roadway.

In the space below the quadrantal wall 24 of the float chamber and of the adjacent chambers 20, which are of similar shape, there is formed a triangular reservoir or sump 29 which extends for the whole of the width of the structure 15, as best seen in Figure 2. In the pump chamber 28 is a centrifugal pump 30 driven by an electric motor 31. The suction pipe 32 of the pump 30 is not shown in Figure 1, but extends as indicated in Figures 6 to 8 from the sump 29 to the pump through a valve 33, the valve 33 being located in the pump house 28 so as to be readily accessible to the operator. The pump delivers through a pipe 34 to the reservoir 27. From the bottom of the reservoir 27 there extends another pipe 35 to a regulating valve 36 which is located in a space at the bottom of one of the quadrantal chambers 20 but to one side of the path of the counterweight 17, close to the wall of the float chamber 19. The valve 36 is operated by a handwheel 37 in the pump house 28 through a vertical shaft 38, gearing 39 and a second vertical shaft 40.

The pipe 35 beyond the valve 36 opens into one side of an automatic regulating valve 41. Beyond the automatic regulating valve 41 there is another hand-operated valve 42 which delivers by pipe 43 into the sump 29. The valve 42 is operated by gearing 44, 45, a vertical shaft 46, gearing 47 and another vertical shaft 48 from a hand-wheel 49 in the pump house 28. From the automatic valve 41 there is a branch 50 extending through a regulating valve 51 into the float chamber 21.

The automatic valve 41, which is shown in detail in Figures 4 and 5, will now be described. The valve 41 is constituted by a rectangular box-shaped casing closed at each side by vertical side plates 53, 54, the inner faces 55 of which constitute valve faces. Over these valve faces there slide regulating valve-plates 57, 58 and the adjacent edges 59, 60 of these plates determine by their distance apart the amount of the valve opening. The plates 57, 58 slide over a port 61 which, as shown in Figure 4, is of a more or less triangular formation with its apex on the left as viewed in the figure.

A branch connection 62 from the inlet conduit 35 leads to two supplementary ports 63, 64 which are shown in dotted lines in Figure 4 and co-operate with ports 65, 66 in the plate 53. A similar pair of plates 57, 58 operate on the outlet face formed by the inner face of the plate 54 of the valve 41. The plates 57 carry racks 70 which engage with opposite sides of a pinion 71 mounted on a vertical operating shaft 72. Similarly the plates 58 carry racks 67 which mesh

with a pinion 68 on a vertical operating shaft 69. Thus when the shaft 72 is operated to move the plate 57 on the inlet 35 toward the left the corresponding plate on the outlet 43 will be moved toward the right. Similarly when the shaft 69 is rotated to move the plate 58 to the left on the inlet 35 the plate 58 on the outlet 43 will be moved in the opposite direction. Thus opening of the inlet will be accompanied by closing of the outlet and vice versa.

A bevel wheel 73 on the pivot shaft 14 operates a bevel wheel 74 on the upper end of the shaft 72. The shaft 69 is actuated, as best seen in Figure 2, by bevel gearing 75 from a horizontal shaft 76 which extends into the float chamber 21 and carries a pinion 77 operated by a spur gear 78 on a sleeve 79 which loosely surrounds the shaft 14. The sleeve 79 has an arm which carries a supplementary float 80 working in the float chamber 21.

With a view to damping the movements of the girder 11 the float 19 is made to fit between the walls of the float chamber 21 closely. Moreover buffers 90, 91 are provided, the former on the underside of the horizontal wall 26 and the latter on the inner side of the vertical wall 25. These buffers are of such size as nearly to fit into recesses 92, 93 which are formed in the counterweight 19 and which are connected together by a conduit 94 passing through the counterweight. When the counterweight approaches the vertical wall 25 in the course of the lifting of the girder 11, the recess 93 fits somewhat closely over the buffer 91 and the liquid trapped between the buffer and the bottom of the recess 93 serves to damp the movement and to bring it to rest, liquid being forced out of the space between the buffer and the bottom of the recess through the conduit 94 and also around the sides of the buffer. In a similar way when the girder has almost reached the position where it abuts upon the abutment 13 the movement is damped by the buffer 90 entering the recess 92.

In the operation of the bridge, when it is desired to lower the bridge the valve 42 is closed and the valves 36 and 51 are opened as shown in Figure 6 so that liquid flows by gravity from the reservoir 27 to the float chamber 21 and fills it. The effective weight of the counterweight is reduced by immersion. It may be stated that the lowest position of the liquid level in the float chamber 21 is about that indicated by the mark 82 in Figure 1 and in this position of the liquid the counterweight 19 will be held firmly in the position indicated by the chain lines in the figure. As soon as the liquid level has risen to about the mark 83 by reason of the flow of liquid from the reservoir 27 the pressure of the counterweight on the buffer 91 will be relieved and further flow of liquid into the float chamber will lower the girder gradually until when the level indicated by the mark 22 is reached the girder will rest upon the abutment 13. The position of the valves during this operation is indicated in Figure 6, and if there is any liquid remaining in the sump 29 during this operation the pump 30 can be kept running. It will therefore be appreciated that it is not necessary for the reservoir 27 to be completely filled before lowering of the bridge takes place.

As the girder 11 approaches the abutment 13 it is desirable that the rate of flow of liquid into the float chamber should be reduced. The rise of the supplementary float 80 operates shaft 69 and tends to move the plate 53 to the left as

viewed in Figure 4. As the girder 11 descends it moves the valve plate 57 also to the left through the gearing connected with the shaft 12. Thus the plate 57 follows the plate 58 across the opening or port 61. If the girder lags in its movement the rate of flow of liquid is automatically increased, but otherwise the plates keep about the same distance apart, and, the port 61 being of a triangular shape, as shown in the drawing Figure 4, with its apex toward the left, the area open to the flow of liquid is gradually reduced as the girder 11 approaches the abutment 13 so that the movement may be slowed down. The parts are so proportioned that when the girder reaches the abutment 13 the port 61 will be wholly closed by plate 57. Thereafter admission of liquid to the float chamber can only take place by the ports 64, 66 and 63, 65 which at this stage are brought into register with one another by movement of plate 58 and allow a sufficient flow of water to continue until the level indicated by the mark 23 has been reached, when the girder 11 will be resting firmly on the abutment 13. When the bridge is in the lowered position the valve 36 is closed and the valves thus assume the position shown in Figure 7.

When the bridge is to be raised a similar series of operations take place but in the reverse direction. The valve 42 is open, as indicated in Figure 8, and liquid flows out of the float chamber 21 into the sump 29. As the girder moves upward it moves the plates 57, 58 across the opening of the valve 41 which lies on the opposite side from the port 61, shown in Figure 4, and regulates the flow into the conduit 43 in a similar way to that already described for the regulation of the flow within the conduit 35. The girder is therefore moved steadily upwards and brought gently to rest in its uppermost position.

The pump 30 can be set running as soon as there is any liquid in sump 29, that is to say, as soon as the bridge commences to rise, and the reservoir 27 can, if desired, be made to hold enough liquid to lower the bridge twice, so that in practice even if conditions call for as much as three successive lowerings in a short period, a pump which can raise only enough liquid to operate the bridge once in this time will suffice.

It will be noted that the valve 51 which connects the automatic valve 41 with the float chamber 21 is permanently open except when it is necessary to effect some attention to the parts in the chamber 20, which can be done by a workman descending into the chamber. The valve 51, therefore, unlike the valves 36 and 42, is not provided with a control operable from the pump house 28.

It is to be observed that although the counterweight has been referred to as a float it need not, in itself, be lighter than the liquid and indeed would not normally be so as the counterweight is in the main balanced by the weight of the girder and the liquid only has to exert a sufficient buoyancy to overcome the excess weight of the counterweight and to hold the bridge, when it is down, firmly down on its abutment.

It is further to be observed that when the bridge is being lifted or lowered there is an automatic action with the construction described which tends to compensate for the effects of wind forces, which, as is well known, may be considerable. Should the wind blow on the girder in such a direction as to tend to depress it, the counterweight is lifted further out of the liquid, increasing the effect of the weight and thus resist-

ing the pressure of the wind. On the other hand if the wind blows on the girder in such a direction as to tend to lift it the counterweight will be depressed and the liquid level in the float chamber will be raised. Owing to the narrow space between the sides of the counterweight and the sides of the float chamber, the variations of liquid level produced in the float chamber by these actions of wind will be quite high for a small movement of the girder and therefore the compensating effect is considerable and the girder will tend to move but little under the influence of wind; taken in conjunction with the damping action on the movement which the liquid exerts this makes for a stable action of the bridge. As already pointed out, when the bridge is lowered the liquid level is made high enough to hold the girder down firmly on its outer abutment; in the same way when the bridge is raised the liquid level is made low enough for the float to be held firmly against the abutment in the float chamber; thus there is no tendency for the bridge to swing out of raised position under wind forces.

Referring now to Figures 9 and 10, these show the construction of a rolling bascule bridge in accordance with the invention. The bridge comprises a triangulated girder 100 which spans an opening 101 and rests at its free end upon an abutment 102. At the other end the sides 103 of the girder are connected to a heavy transverse shaft 104 which is located at the centre of the rolling surfaces 105 of the bascule. The rolling surfaces are formed upon two large counterweights 106, 107 which are carried on plates 108, 109 rigidly secured to the ends of the shaft 104. The counterweights 106, 107 are spaced by the shaft 104 from the sides of the girder 103 and the counterweights rest on the bottom of float chambers 110, 111. The float chambers are shaped to be a fairly close fit against the sides of the counterweights and to afford no more than enough room for the weights to roll back into the position in which the girder 100 is fully lifted. The bottoms of the float chambers 110, 111 are provided with heavy rolling plates or sole plates on which the surfaces 105 can roll with ease and preferably oil is used as the floating medium in the float chambers 110, 111. Appropriate sump, reservoir and pumping apparatus is provided, which is not shown in the drawings, so that the float chambers 110 and 111 can be filled or emptied at will. When the float chambers are filled to the level indicated by the chain line 113 the girder 100 will reach abutment 102 and on being further filled to the level indicated by the chain line 114 the girder will be pressed firmly down upon the abutment. The weight 115 is an additional counterweight mounted directly upon a rearward extension of the girder 100. The oil in the float chambers tends to keep the rolling surfaces clean and to reduce operating friction.

In the case of a swing bridge or dock gates the counterweight can be connected to the bridge girder or to the gates by an appropriate link-work. Again it is possible with a swing bridge to make the girder pivot spherical so that the girder is free not only to swing laterally but also to rise and fall. A counterweight can be provided to the girder that rides in a quadrantal tank or float chamber concentric with the spherical pivot and a cam may be provided which extends around the quadrantal wall of the float chamber and engages a roller on the counterweight. The effect is that if the tank is emptied the counterweight presses on the cam and the cam deflects the

bridge around the quadrant, allowing the counterweight to fall while the bridge is swinging; the bridge therefore falls at the counterweight end and rises at its opposite end while swinging round the pivot and executes a movement which is a combination of a lifting and a swinging movement.

I claim:

1. A bascule bridge comprising in combination a tiltably-mounted bridge girder, a counterweight rigidly connected thereto and means to vary at will the effective weight of the counterweight by adding or withdrawing liquid in contact therewith under the control of the operator.

2. A bascule bridge as claimed in claim 1, wherein the counterweight is located in a float chamber so as to constitute a float therein and the means for introduction and withdrawal of liquid are constituted by means for varying the liquid level in the float chamber.

3. A bascule bridge comprising in combination a bridge girder which is mounted on a pivot, a counterweight rigidly secured to the bridge girder and projecting beyond the pivot, a float chamber in which the counterweight moves and means to vary the liquid level in the float chamber to raise and lower the girder.

4. A bascule bridge as claimed in claim 3, wherein the counterweight and float chamber are located beneath the floor level of the bridge.

5. A bascule bridge as claimed in claim 3, wherein an additional counterweight is provided, not located in the float chamber, the counterweights being secured upon the pivot shaft of the bridge girder.

6. A bridge as claimed in claim 3, wherein the flow of liquid out of the float chamber for the purpose of raising the bridge is effected by gravity and the rate of flow is regulated automatically so as to be reduced as the bridge rises by means of a valve operated by the moving parts of the bridge.

7. A bridge as claimed in claim 3, wherein the flow of liquid out of the float chamber for the purpose of raising the bridge is effected by gravity and the rate of flow is influenced as the bridge rises by means of a valve operated by a supplementary float in the float chamber.

8. A bascule bridge as claimed in claim 3, wherein the means to vary the liquid level includes a regulating valve to control admission of liquid to and withdrawal thereof from the float

chamber, movable valve means in the regulating valve operatively connected to the counterweight to be actuated thereby, other movable valve means in the regulating valve operatively connected to a supplementary float in the float chamber to be actuated thereby, the operative connections to both said movable valve means being such that during supply of liquid to the float chamber the movable valve means move together across a shaped inlet port to reduce the rate of flow as the bridge descends and during raising of the bridge other parts of both said movable valve means move together across a shaped outlet port to reduce the flow towards the end of the rise of the girder.

9. A bascule bridge as claimed in claim 3, wherein a reservoir is provided above the level of the float chamber and the filling of the float chamber is effected through a communication conduit extending from the reservoir to the float chamber and controlled by a regulating valve in the conduit.

10. A bascule bridge as claimed in claim 3, wherein the float chamber is connected by a conduit to a sump, the conduit containing a regulating valve, and the sump is located beneath the level of the float chamber so that the chamber can be emptied by gravity.

11. A bascule bridge as claimed in claim 3, wherein the means for varying the liquid level in the float chamber comprise a reservoir above the level of the float chamber, a sump below the level of the float chamber, conduit means connecting the reservoir, the sump and the float chamber together, regulating valve means in said conduit, means for permitting liquid to flow from the reservoir into the float chamber when desired and from the float chamber into the sump when desired and a pump for raising liquid from the sump to the reservoir.

12. A bridge comprising in combination a rolling bascule girder, a float-chamber located on each side of said girder at one of the abutments thereof, two counterweights, one on each side of the girder, secured to the girder and each dipping into one of the float-chambers, the two counterweights being shaped to provide rolling surfaces which roll on the abutments of the float-chambers and means to introduce or withdraw liquid to or from the float-chamber at will for raising and lowering the girder.

ALAN EDWARD SPENCE TEMPLE.
